CLAIM

I claim the ornamental design for a faceplate, as shown and described.

DESCRIPTION

FIG. 1 is a top, front, left perspective view of a faceplate showing my new design;

FIG. 2 is a front elevation view thereof;

FIG. 3 is a top plan view thereof, the bottom plan view

thereof being a mirror image of the top plan view shown;

FIG. 4 is a right side elevation view thereof, the left side elevation view thereof being a mirror image of the right side elevation view shown; and,

FIG. 5 is a cross-sectional view thereof taken along line 5-5 of FIG. 2.

The ornamental design which is claimed is shown in solid lines in the drawings. The broken lines in the drawings are for illustrative purposes only and form no part of the claimed design. Broken lines formed by equal length dashes in the drawings illustrate unclaimed portions of the design. Broken lines formed of unequal length dashes (i.e., dash-dot) show boundaries between claimed and unclaimed portions of the design. Portions shown in stipple shading as opposed to line shading show contrasting surfaces unlimited by color, texture, or surface finish.
